CLAIM

What is claimed is the ornamental design for a push-button for door lever/handle, as shown and described.

DESCRIPTION

FIG. 1—is a perspective view of a push-button for door lever/handle;

FIG. 2—is a front view thereof;

FIG. 3—is the back view thereof;

FIG. 4—is a right side view thereof;

FIG. 5—is a left side view thereof;

FIG. 6—is a top view thereof; and,

FIG. 7—is a bottom view thereof.

The broken lines shown represent unclaimed subject matter and form no part of the claimed design.
